COMBINED ELECTRIC CAN OPENER AND FOOD SHREDDER

Daniel E. McCue, Santa Barbara, Calif., assignor to Rival
Manufacturing Company, Kansas City, Mo.

Filed May 24, 1973, Ser. No. 363,595

Term of patent 14 years

Int. Cl. D7—99

U.S. Cl. D8—34

Fig. 1.

Fig. 2.

Fig. 3.

Fig. 4.

Fig. 5.

Fig. 6.

FIG. 1 is a rear perspective view of a combined electric can opener and food shredder showing my new design;

FIG. 2 is a front elevational view of same;

FIG. 3 is a side elevational view taken from the left hand side of FIG. 2;

FIG. 4 is a side elevational view taken from the right hand side of FIG. 2;

FIG. 5 is a rear elevational view; and

FIG. 6 is a top plan view.

The bottom of the combined electric can opener and food shredder is plain except for the support runners and the conventional folding wire bail.

I claim:

The ornamental design for a combined electric can opener and food shredder, as shown and described.
